29 Claims

ABSTRACT OF THE DISCLOSURE

The compounds are of the class of Nobel nitro dyes, useful in a silver dye bleaching method of color photography, having as the chromophore a nitro group, and as the auxochrome —OX (wherein X represents a hydrogen atom, an alkali metal or 1/2 calcium and ammonium) or —NHY (wherein Y represents a hydrogen atom, a lower alkyl group, a substituted alkyl group, a cyclic alkyl group, an aryl group and a substituted aryl group), and the —NHY may form a ring together with —O— or —N—R (wherein R is an aryl group or a substituted aryl group).

BACKGROUND OF THE INVENTION

(1) Field of the invention

The present invention relates generally to a photographic color process and particularly to a process for obtaining color photographs by a silver dye bleaching method.

(2) Description of the prior art

The production of photographic color images by a silver dye bleaching method is based on the fact that certain types of dyes are destroyed by a suitable treatment in the presence of metallic silver. In a silver dye bleaching method, after exposure and development, a photographic gelatine-silver halide emulsion layer which is uniformly colored with a proper dye is processed in a bleaching bath capable of simultaneously oxidizing the silver image formed and reducing (bleaching) the dye at the areas having the silver images. The silver salts and remaining metallic silver are then removed to provide a reversal dye image of the initial silver image. By this process, a monochromatic image or a multi-color image can be obtained. For these purposes, there have hitherto been used azo dyes, anthraquinone dyes, indigo dyes, and phthalocyanine dyes.

The dye used in the silver dye bleaching method must be one which can be easily bleached by a bleaching bath in proportion to the amount of photographic silver image and can also be completely bleached at the areas of maximum silver image density. In addition, the dye must have good fastness to light. It is desirable that the individual dyes forming multi-color images satisfy, as completely as possible, the theoretical requirement that each dye completely absorbs only blue, green, or red light, and completely transmits or reflects the other two kinds of light. Therefore, it is desirable to provide a process of obtaining photographic color images by a silver dye bleaching method using a dye satisfying the aforesaid conditions.

SUMMARY OF THE INVENTION

The present invention is based on the discovery of the fact that nitro dyes can be bleached by a photographic silver image in a step of a silver dye bleaching method. By nitro dye is meant a dye having as the chromophore a nitro group and as the auxochrome —OX (wherein X

2

represents a hydrogen atom, an alkali metal, 1/2 calcium or ammonium) or —NHY, (wherein Y represents a hydrogen atom; a lower alkyl group; a substituted alkyl group, such as an aminomethyl group or a hydroxyethyl group, a cyclic alkyl group; an aryl group; or a substituted aryl group such as a hydroxyphenyl group or sulphonaphthyl group) which may form a ring together with —O— or

(wherein R represents an aryl group or a substituted aryl group such as a methoxyphenyl group) which is at the ortho position to —NHY.

DESCRIPTION OF THE PREFERRED EMBODIMENTS

Among these nitro dyes a preferable dye is a nitrobenzene or a nitronephthalene having —OX or —NHY (X and Y are as defined above) at the ortho-position to the nitro group. In addition, the benzene ring or the naphthalene ring may be substituted with at least one of the following: a nitro group, a lower alkyl group, an aryl group, a substituted aryl group such as a nitro phenyl group, an amino group, a cyano group, a halogen atom, a carboxyl group, a sulfonic acid group, —SO₂R₁ (where R₁ represents an aryl group or a substituted aryl group such as a nitro-phenyl group), and

(R₂ and R₃ each represent a hydrogen atom, a lower alkyl group, a substituted alkyl group such as an aminomethyl group or a hydroxyethyl group, a cyclic alkyl group, an aryl group or a substituted aryl group such as a hydroxyphenyl group). The typical examples of the nitro dyes used in this invention are as follows:

Color Index Compound No. 10300

Color Index Compound No. 10302

Color Index Compound No. 10306

Color Index Compound No. 10310

(27)

Color Index Compound No. 10435

(28)

Color Index Compound No. 10440

(29)

The above nitro dyes are identified according to their Color Index Compound Number. The Color Index Compound Number can be found in Color Index, Part II, vol. 3 (1956), and the Supplement (1963) thereto, published by the Society of Dyers & Colorists. These references describe the nitro dyes, their properties and their methods of preparation. Nitro dye (20) identified by Color Index Number Dis. 8, can be found in "Senryo Binran (Dyestuff Handbook), edited by Yuki Gosei Kagabu Kyokai (The Organic Synthetic Chemical Society) and published in 1959. As disclosed therein, the method of preparing this dye is by the condensation of aniline with 3-nitro-4-chlorobenzene sulfonamide.

The dyes shown by the above structures (3), (18), (19) and (22)–(28) have a brownish color hue and hence can be used as the dyes for mono-chromatic light-sensitive elements, for example, the copying light-sensitive elements described in the specifications of British Pats. 999,996 and 1,002,345. By exposing a silver halide emulsion layer colored by such a dye through a black and white original, developing and fixing as in a conventional silver dye bleaching method, processing the layer in a dye bleaching bath to form a color image, and removing remaining silver, a positive copy can be obtained.

As is well known, nitro dyes have been employed for dyeing natural fibers such as wool and cotton or artificial fibers such as acetates, polyamides, and polyesters. Many nitro dyes as well as the preparation processes thereof are known.

6

In the present invention, the nitro dye is used for dyeing a colloid, such as gelatin or poly-vinyl alcohol, for forming a photographic layer. In particular, the nitro dye is used as a dye for forming the yellow image of a multiple layer light-sensitive color element such as a light-sensitive negative color element or a light-sensitive positive color element the image of which may be observed by transmitted light or reflected light. A colloid for forming a light-sensitive layer is colored by the nitro dye and then mixed with a silver halide emulsion. The resulting mixture may be applied to a support as a photographic layer. Alternately, the dye may be brought into contact with an emulsion layer to be incorporated into the layer which consists of only the above-mentioned colloid, such as a layer consisting only of gelatin. Furthermore, after exposure or development, the emulsion layer may be colored with the nitro dye. These nitro dyes may be used in the same manner as conventionally employed dyes.

In the case of a water-soluble nitro dye, the dye can be mixed in a gelatin solution or a photographic emulsion as an aqueous solution thereof. In the case of a water-insoluble dye, the dye is dispersed in a gelatin solution or a photographic emulsion by using a dispersing agent such as sodium alkylbenzene sulfonic acid. Moreover, a nitro dye soluble in an organic solvent may be dissolved in an organic solvent and the solution thus obtained may be mixed in a gelatin solution or a photographic emulsion, or the organic solvent solution may be emulsion-dispersed in gelatin by using a surface active agent. In addition, after exposing and developing, an uncolored photographic emulsion layer may be dyed with an aqueous solution of a water-soluble nitro dye. The colored layer obtained is then used, for example, as a component of a two or three-color system.

Suitable organic solvents are alcohols such as methanol, ethanol, ethylene glycol, a monoalkyl ether of ethylene glycol, and a monoalkyl ether of diethylene-glycol, esters such as ethyl acetate and butyl acetate; ethers such as ethyl ether, dioxane, and tetrahydrofuran, ketones such as acetone and methylethylketone; amides such as lactams and dialkylcarbamides; and the like. Moreover, high boiling point oily solvents may be employed. For example, alkyl esters of phthalic acid such as dibutyl phthalate, dioctyl phthalate, etc., phosphoric acid esters such as tri-phenyl phosphate and tricresyl phosphate; alkylamides such as dibutylaurylamide and acetanilides such as N-butylacetanilide.

As the dye bleaching bath, known acid bleaching baths may be used. The bleaching bath contains a solvent for silver such as thiourea, semicarbazide, etc., and an alkali metal halide such as sodium chloride, potassium bromide, etc. The bleaching bath may contain as a catalyst an accelerator used in the bleaching processing of an azo dye in a conventional silver dye bleaching method, such as anthraquinone sulfonic acid, dimethylquinoxaline, amino-hydroxyphenazine, and the like.

According to the present invention, an image having utterly colorless highlight portions can be obtained since the nitro dye can be easily bleached and hence the bleaching can be completely conducted.

The invention will be explained in more detail by referring to the following examples.

EXAMPLE 1

65 Into 2 ml. of tricresyl phosphate was dissolved 0.2 g. of C.I. Disperse Yellow 42 represented by aforesaid structure (21). The solution obtained was added into 10 ml. of a 10% aqueous gelatin solution containing 2 ml. of a 10% aqueous solution of sodium alkyl-benzene sulfonate and subjected to dispersing by means of a homoblender. After mixing 6 g. of the dispersion with 20 g. of a silver bromide photographic emulsion (containing about 30 g. of silver bromide per one kg. of emulsion), the resulting mixture was applied on a glass plate.

7

The light-sensitive plate was exposed through a step wedge and then developed for 10 minutes in a developer having the following composition.

	G.
N-methyl-p-aminophenol 1/2. sulfate	2
Sodium sulfite (anhydrous)	30
Hydroquinone	8
Sodium carbonate (mono-hydrate)	20
Potassium bromide	4
Water to make 1 liter.	

The plate was then washed with water and fixed for 4 minutes in a fixing solution having the following composition:

	G.
Sodium thiosulfate (anhydrous)	350
Sodium sulfite (anhydrous)	10
Water to make 1 liter.	

The plate was washed with water, hardened with a 10% aqueous solution of formaldehyde, and then washed with water again. The plate was then processed for 15 minutes in a dye bleaching solution having the following composition:

Thiourea—60 g.	
Potassium bromide—30 g.	
Concentrated hydrochloric acid—30 ml.	
2-amino-3-hydroxyphenazine—0.01 g.	
Water to make 1 liter.	

The plate thus bleached was then washed with water and subjected to silver bleaching in a solution having the following composition:

Crystalline copper sulfate—100 g.	
Concentrated hydrochloric acid—100 ml.	
Water to make 1 liter.	

The plate was then washed with water, fixed in a fixing bath having the same composition as shown above, washed again with water, and dried. A yellow dye image having excellent light fastness and a lemon-yellow hue was obtained. Bleaching of highlights was complete, and the blue optical density was 0.12. This is particularly suitable as an image of a yellow component in a multiple color type light-sensitive element. For comparison, the same procedure as above was repeated using the conventional yellow azo dye having the following structure to provide an image. The blue optical density of the highlight portion was only 0.35.

EXAMPLE 2

The same procedure as in Example 1 was repeated using 4 ml. of ethyl acetate instead of 2 ml. to tricresyl phosphate and almost identical results were obtained.

EXAMPLE 3

By repeating the same procedure as in Example 1 while using 2 ml. of dibutyl phthalate and 1 ml. of butyl acetate instead of 2 ml. of tricresyl phosphate, almost identical results were obtained.

EXAMPLE 4

By repeating the same procedure as in Example 1 while using C.I. Disperse Yellow 14, shown by the above-mentioned structure (12), instead of C.I. Disperse Yellow 42 in Example 1, a yellow image was obtained.

EXAMPLE 5

By repeating the same procedure as in Example 1 while using the dye shown by structure (9) instead of C.I.

8

Disperse Yellow 42 in Example 1, a yellow image was obtained.

EXAMPLE 6

By repeating the same procedure as in Example 1 while using the dye shown by structure (11), a yellow image was obtained.

EXAMPLE 7

10 Into 40 ml. of water, 0.4 g. of C.I. Disperse Yellow 33 shown by structure (20) was dispersed. The dispersion was mixed with 50 g. of a silver bromide emulsion (containing about 30 g. of silver bromide per one kg. of emulsion), and the mixture was applied to a glass plate. The light-sensitive plate was exposed and processed as in Example 1 to provide a yellow wedge image.

EXAMPLE 8

20 Into 100 ml. of water, one g. of C.I. Acid Yellow 20 shown by structure (7) was dissolved. After mixing 80 ml. of the solution of the dye with 100 g. of a silver bromide emulsion (containing about 30 g. of silver bromide per one kg. of emulsion), the mixture was applied to a glass plate. The dye was fixed in the emulsion layer by a precipitant such as diphenylguanidine (described in the specification of U.S. Pat. 2,172,308). The light-sensitive plate was exposed through a step wedge, developed in a developer containing N-methyl-p-aminophenol 1/2 sulfate and hydroquinone, and then fixed. The plate was then hardened by a diluted solution of formaldehyde and thereafter processed in a dye bleaching bath containing 30 ml. of concentrated hydrochloric acid, 30 g. of potassium bromide and 60 g. of thiourea per one liter of bleaching bath. After bleaching remaining silver in a copper sulfate bath strongly acidified by hydrochloric acid, the plate was fixed in a conventional manner. A yellow dye image was obtained.

EXAMPLE 9

40 Into 300 ml. of a 10% aqueous gelatin solution, 2 g. of C.I. Acid Yellow 24 shown by structure (6) was dissolved. The colored gelatin solution was applied to a dry-thickness of 3 microns to a silver halide emulsion layer of 7 microns dry-thickness coated on a glass plate. 45 When the light-sensitive plate was processed as in Example 1, a yellow image was obtained in the colored gelatin layer in proportion to the silver image formed in the silver halide emulsion layer.

EXAMPLE 10

50 A standard photographic light-sensitive black and white film was exposed, developed, and fixed in the conventional manner. The film was dyed for about 20 minutes at room temperature in a 2% aqueous solution 55 of C.I. Acid Yellow 24 shown by structure (6). In this case, a dyeing aid may be added as in standard dyeing techniques. After dyeing, the film was subjected to the dye bleaching and subsequent processings as in Example 1 to provide a yellow image.

60 What is claimed is:

1. In a silver dye bleaching method which comprises exposing to light a photographic light sensitive element comprising a silver halide containing emulsion layer uniformly colored with at least one bleachable nitro aryl dye, processing and subsequently bleaching said element, the improvement wherein said dye is a bleachable nitro aryl dye having as the chromophore a nitro group and as the auxochrome a member selected from the group consisting of —OX, wherein X represents a member selected from the group consisting of a hydrogen atom, an alkali metal, 1/2 calcium and ammonium, and —NHY, wherein Y represents a member selected from the group consisting of a hydrogen atom, a lower alkyl group, a substituted alkyl group, a cyclic alkyl group, an aryl

9

group and a substituted aryl group, said $-\text{NHY}$ having the capability of forming a ring together with a member selected from the group consisting of $-\text{O}-$ and

wherein R is selected from the group consisting of an aryl group and a substituted aryl group, which is at the ortho position to $-\text{NHY}$.

2. A process as in claim 1 wherein Y represents a substituted alkyl group selected from the group consisting of an aminomethyl group and a hydroxyethyl group.

3. A process as in claim 1 wherein Y represents a substituted aryl group selected from the group consisting of a hydroxyphenyl group and a sulfonaphthyl group.

4. A process as in claim 1 wherein R represents a methoxyphenyl group.

5. A process as in claim 1 wherein the dye is nitrobenzene having $-\text{OX}$ or $-\text{NHY}$ at the ortho-position to the nitro group.

6. A process as in claim 5 wherein the dye is substituted with at least one member selected from the group consisting of a nitro group, a lower alkyl group, an aryl group, a substituted aryl group such as a nitrophenyl group, an amino group, a cyano group, a halogen atom, a carboxyl group, a sulfonic acid group, $-\text{SO}_2\text{R}_1$ (wherein R_1 represents a member selected from the group consisting of an aryl group and a substituted aryl group such as a nitrophenyl group),

(wherein R_2 and R_3 may be selected from the group consisting of a hydrogen atom, a lower alkyl group, a substituted alkyl group selected from the group consisting of an amino methyl group and a hydroxy ethyl group, a cyclic alkyl group, an aryl group and a substituted aryl group such as a hydroxyphenyl group).

7. A process as in claim 5 wherein the dye is nitronaphthalene.

8. A process as in claim 6 wherein the dye is nitronaphthalene.

9. A process of obtaining color photographs by a silver dye bleaching method as described in claim 1, using a nitro dye having the formula:

10. A process of obtaining color photographs by a silver dye bleaching method as described in claim 1 using a nitro dye having the formula:

11. A process of obtaining color photographs by a silver dye bleaching method as described in claim 1 using a nitro dye having the formula:

12. A process of obtaining color photographs by a

10

silver dye bleaching method as described in claim 1 using a nitro dye having the formula:

13. A process of obtaining color photographs by a silver dye bleaching method as described in claim 1 using a nitro dye having the formula:

14. A process of obtaining color photographs by a silver dye bleaching method as described in claim 1 using a nitro dye having the formula:

15. A process of obtaining color photographs by a silver dye bleaching method as described in claim 1 using a nitro dye having the formula:

16. The process as claimed in claim 1 wherein said nitro dye is incorporated in a photographic silver halide light-sensitive emulsion layer in said photographic light-sensitive element.

17. A process as in claim 16 wherein the nitro dye is used as a dye for dyeing a colloid in the photographic light-sensitive element so as to form the yellow image of a multiple layer light-sensitive element, said colloid being selected from the group consisting of gelatin and polyvinyl alcohol.

18. A process as in claim 16 wherein a colloid for forming a light-sensitive layer in said photographic element is colored by the nitro dye and then mixed with a silver halide emulsion for subsequent application to a support.

19. A process as in claim 16 wherein a water soluble nitro dye is mixed in the sensitive emulsion layer as an aqueous solution thereof.

20. A process as in claim 16 wherein a water insoluble nitro dye is dispersed into the sensitive emulsion layer by using a dispersing agent.

21. A process as in claim 16 wherein a nitro dye soluble in an organic solvent is formed into a solution, and the solution thus obtained is mixed with the sensitive photographic emulsion.

22. The process as claimed in claim 1 wherein said nitro dye is incorporated in a gelatin layer adjacent to a photographic silver-halide light-sensitive emulsion layer.

23. A process as in claim 22 wherein a water soluble nitro dye is mixed into the gelatin emulsion by dissolving it in an aqueous gelatin solution.

24. A process as in claim 22 wherein a water soluble nitro dye is dispersed into the gelatin emulsion by using a dispersing agent.

25. A process as in claim 22 wherein a nitro dye soluble in an organic solvent is formed into a solution therewith and mixed with a gelatin solution.

75

26. A process as in claim 22 wherein the organic solvent solution is emulsion dispersed in gelatin by using a surface active agent.

27. The process as claimed in claim 1 wherein, after exposing and processing, said bleaching of said nitro dye is accomplished by subjecting said element to a dye bleaching bath.

28. A process as in claim 27 wherein the dye bleaching bath contains a solvent for silver and an alkali metal halide.

29. A process as in claim 27 wherein the dye bleaching bath contains, as a catalyst, a dye bleaching accelerator.
